UNITED STATES PATENT OFFICE

ROBERT W. KALTENBACH, OF CLEVELAND HEIGHTS, OHIO

CAR DUMPER CHUTE CONTROL MECHANISM

Application filed December 5, 1930. Serial No. 500,300.

This invention relates to car dumpers and particularly to those having a discharge chute, which is mounted adjacent the end of the pan or conveyor, by means of which material is fed to the chute.

To facilitate proper disposition and trimming of the load, it is expedient to have the lower end of the chute mounted for universal movement with reference to the upper end thereof. This has been accomplished by utilizing four cables that extend downwardly along the chute and are connected to the lower end thereof adjacent the four corners of a rectangle. Thus, when any two cables on one side of the rectangle are wound in, and those on the opposite side are paid out, the lower end of the chute can be swung with reference to the pan or support, the direction of such motion depending upon the manner in which the cables are grouped for operation.

The mechanism heretofore used for operating the cables has embodied a single source of power, such as a steam engine, or a single electric motor, while suitable gearing and clutches have connected the motive power to the respective cables. The space limitations for such mechanism has been so restricted, that it has been difficult to make it sufficiently heavy and rugged to manipulate the load. This is particularly noticeable when the chute is fully extended and is filled with material. At such time, it is hard to manipulate the clutches particularly, as the control house is usually mounted on an extension of the pan or conveyor and remote from the mechanism. Accordingly, it has been necessary to connect the control levers with the clutches by means of long rods, ropes and chains which in turn have required additional space for suitable linkage in order to permit operation of the clutches without requiring the operator to expend an excessive amount of energy in the manipulation thereof.

I have found however, in spite of the mechanical refinements, which were developed to facilitate the operation of the clutches and brakes, that the system is far from satisfactory, for it is very difficult to manipulate the control rods to swing the lower end of the

chute accurately and quickly to any desired position. Furthermore, it cannot be accomplished without the expenditure of considerable energy by the operator.

The object of the present invention is to provide a method by means of which the movement of the chute can be accurately and quickly controlled without requiring any of the mechanical control devices, such as lever operated clutches and brakes; thus dispensing entirely with the need for mechanically actuated connecting devices between the cable operating mechanism and the control house. In this connection, my invention contemplates the provision of an apparatus, by means of which the chute may be controlled more efficiently than heretofore, and without resulting in undue fatigue to the operator.

The preferred means for carrying out my invention is shown in the drawings, wherein Fig. 1 is a diagrammatic side elevation of a car dumper embodying my invention; Fig. 2 is an end elevation of part of the chute shown in Fig. 1; Fig. 3 is a plan view of the control and operating mechanism for actuating the chute cables; Fig. 4 is a diagrammatic view illustrating the relationship of the cables to the actuating means therefor; Fig. 5 is a wiring diagram, and Fig. 6 is a top plan diagrammatic view illustrating the cable arrangement.

Briefly, my invention in general embodies an arrangement of cables adjacent the top and bottom of the chute in substantially the same manner as heretofore, except that I now utilize a separate motor for each cable. I then provide suitable control mechanism, by means of which the motors may be grouped into pairs to swing the chute in one plane, and by means of which the grouping may be rearranged to swing it in a complementary plane. Thus, the operator in the control room, need only move the required circuit controllers to effect the desired result.

Referring now in detail to the drawings, 10 indicates the frame of a car dumper, 11 a cradle and 12 a car thereon. In the full line position of Fig. 1, the cradle is shown in elevated position and in dumping position,

while in the broken line position 11a, the cradle is shown in the car receiving position. The dumper illustrated includes a pan 13, the lower end of which converges to form a restricted passageway 14, which communicates with the discharge chute 15. The lower end of such chute is arranged for universal movement with reference to the pan, and to this end, I have illustrated different positions of 10 the chute in one plane as at 15a and 15b in Fig. 1. In Fig. 2, other positions in a plane complementary to that shown in Fig. 1 are illustrated at 15c and 15d respectively.

15 The chute itself comprises a plurality of telescopically interconnected tubular sections. The uppermost section 16 is pivotally connected at 17 to the discharge end of the pan, and overlaps a curved stationary section 18 that is fastened to the end of the 20 pan. The curvature of the section 16 corresponds to that of section 18, so as to permit the flow of the pan contents into the chute, when the chute assumes the position such as that indicated at 15a and 15b.

25 The chute motion indicated in Fig. 1 is termed "athwart" motion, while the complementary motion is termed "fore" and "aft" motion, and is obtained by reason of the fact that the upper section 16 is pivotally connected at 19 to the adjacent section 20.

30 The means for controlling the movement of the lower end chute with reference to the upper end thereof embodies four cables 30, 40, 50 and 60 which are mounted on drums 31, 41, 51 and 61 respectively. The drums in turn are adapted to be operated by independent electric motors 32, 42, 52 and 62 through suitable reduction gearing 33, 43, 53 and 63 respectively. Furthermore, each 35 motor is provided with automatic solenoid braking mechanism indicated in general at 34, 44, 54 and 64 respectively.

35 The reeving of the cables is as follows: Cables 30 and 40 pass over guide sheaves 70 and 71 which are shown as being supported adjacent the upper end of the chute and on the underside of the pan, and thence over sheaves 72 and 73 which are pivotally mounted adjacent the lower end of the chute. Such 40 cables constitute the rear group. The front group comprises cables 50 and 60, which pass over sheaves 74 and 75 adjacent the upper end of the chute, and thence over sheaves 76 and 77 adjacent the lower end of the chute. The 45 ends of the respective cables are shown, as being attached to the lower sheave blocks.

50 It is apparent from an examination of Fig. 6, that the upper guide sheaves are spaced adjacent the four corners of a rectangle and are relatively far apart, while the lower guide sheaves are spaced adjacent the corners of a rectangle and are relatively close together. Thus, when the cables associated with one 55 side of the rectangle are wound in, while those at the opposite side are paid out, the

chute will be swung about either of the pivots 17 and 19. The direction of such swinging movement will depend upon the manner in which the motors are operated to wind and pay out the cables. Thus, for example, if 70 cables 30 and 40 are wound in, while 50 and 60 are paid out, the chute will be swung from the full line position in Fig. 1 in the direction indicated by the broken lines 15a. If the direction of rotation of the motors should 75 be reversed, that is, to wind in cables 50 and 60 and pay out cables 30 and 40, then the chute will be moved in the direction indicated toward the position 15b. Such motion takes place about the pivot 17 and provides the "athwart" motion. The "fore" and "aft" motion about the pivot 19 is accomplished by winding in the cables 30 and 50, while paying out cables 40 and 60 or by winding in cables 40 and 60, while paying 85 out cables 30 and 50.

80 To provide the desired selective control, each motor is preferably reversible and the electrical connections between the motors and the circuit controllers are such, that the motors operating the cables to be grouped are simultaneously actuated. Furthermore, each motor is automatically locked against rotation by the solenoid brake as soon as the current is interrupted therethrough.

85 The wiring diagram illustrated in Fig. 5 shows an arrangement whereby the grouping of the motors can be accomplished. In such diagram, the source of power is indicated at 100 while shiftable controller members are indicated at 101, 102, 103 and 104 respectively. The connections for such controllers are preferably so arranged that one controller actuates two motors that are intended 90 to be grouped together for simultaneous 100 movement in one direction. Likewise the two remaining motors are grouped to cause simultaneous movement when desired in the opposite direction. Preferably, the two controllers are independent so that the motors which are used for operation in one direction 105 may be operated either with or without operation of the remaining motors. This feature is desirable, as it facilitates manipulation of the chute in accordance with the shape and condition of the vessel into which the material 110 is being transferred.

115 Considering now a specific direction of chute movement, such for example, as an "athwart" motion wherein the cables 30 and 40 are wound in, the controller 101 is moved to the left in Fig. 5. At such time, current 120 will flow from the source of power through lines 106, 107, contact point 108, contact member 109, line 110 to motor 42 and thence 125 returning through line 111, contact member 112, contact 113, lines 114, 115, 116, 117 and 118 to the source of power. Such current flow 130 will operate the motor 42, for example, in a clockwise direction. At the same time, cur-

rent for energizing the motor 32 will flow from line 107 through line 119, contact 120, member 121, line 122, through motor 32, and thence through line 123, member 124, contact 125, lines 126, 116, 117 and 118 to the source of power.

It will thus be seen that movement of the controller 101 to the left operates the motors 32 and 42 in a clockwise direction to wind in cables 30 and 40. If at the same time, it is desired to operate motors 52 and 62 in a counter clockwise direction so as to pay out cables 50 and 60, then the controller 102 is moved to the right. The current for motor 62 will then flow from the source of power through lines 106, 107, 127, 128, contact 129, member 130, line 131, through motor 62 and thence back through line 132, member 133, contact 134, lines 135, 116, 117, 118 to the source of power. Similarly, current for motor 52 will flow through lines 106, 107, 127, 136 contact point 137, contact member 138, line 139, through motor 52, and thence back through line 140, member 141, contact point 142, thence through lines 143, 116, 117 and 118 to the source of power.

Thus, simultaneous movement of the controller 101 to the left and controller 102 to the right causes rotation of motors 32 and 42 in a clockwise direction, and rotation of motors 52 and 62 in a counter clockwise direction. This arrangement, as heretofore stated, winds in cables 30 and 40 and pays out cables 50 and 60, and enables the chute 35 to be moved to the full line position indicated at 15a in Fig. 1.

To move the chute in a "fore" and "aft" direction, either by winding in on cables 30 and 50, or on cables 40 and 60 depending upon the desired direction of movement, provision is made for grouping the motors for operating such cables, by manipulation of controllers 103 and 104. For example, when controller 103 is shifted to the left, current flows from the source of power through line 106, contact point 145, member 146, line 147, line 110, through motor 42, thence back through lines 111, 148, member 149, stationary contact point 150, lines 151, 152, and 118 to the source of power. This causes rotation of motor 42 in a direction, to wind in the cable 40, which can be assumed, as being in a clockwise direction. At the same time, motor 62 is energized by current which flows from the source of power through lines 106 and 153, stationary contact point 154, contact member 155, line 156, line 132, motor 62, and thence through lines 131, 157, contact member 158, stationary contact point 159, lines 151, 152 and 118 to the source of power.

To group motors 32 and 52 so as to wind in cables 30 and 50, controller 104 may be shifted to the left at which time, current may flow from the source of power through lines 106, 107, 160, 161, stationary contact point

162, contact member 163, lines 164 and 122 to the motor 32, thence back through lines 123, 165, contact member 166, stationary contact point 167, lines 168, 152 and 118 to the source of power. At the same time, current flows from the source of power through lines 107, 160, 169, stationary contact point 170, contact member 171, lines 172, 140, motor 52, lines 139, 173, contact member 174, stationary contact point 175, lines 176, 151, 152 and 118 to the source of power.

The controller arrangement just described is such that by shifting any controller to the left, the two motors controlled thereby operate in a direction to wind in the associated cables. The connections are also shown that will reverse the direction of motor rotation when the controllers are shifted to the right. Considering first that controller 101 is shifted to the right, then current flows from the source of power through lines 106, 107, stationary contact point 108, contact member 112, line 111 through motor 42, thence back through line 110, member 109, stationary contact 177, lines 178, 115, 116, 117, 118 to the source of power. At the same time, current through the line divides and flows through line 119, stationary contact point 120, member 124, line 123, motor 32, thence back through line 122, member 127, contact point 179, lines 180, 116, 117 and 118 to the source of power.

The direction of current flow through motors 52 and 62 has been described in connection with the shifting of the controller 102 to the right. Such direction has been such that the associated cables would be paid out. If, however, the controller is shifted to the left, then the current flowing through the motors will be reversed, thus causing the cables to be wound in, and at such time, the current will flow through lines 106, 107, 127, 128, point 129, member 133, line 132, through motor 62, thence back through line 131, member 130, point 181, lines 182, 116, 117 and 118 to the source of power. At the same time, current through line 127 divides, part going through line 136, point 137, member 141, line 140, motor 52, line 139, member 138, point 183, lines 184, 116, 117 and 118 to the source of power.

When the controller 103 is shifted to the right, current flows from the source of power through lines 106, point 145, member 149, lines 148, 111, through motor 42, thence back through lines 110, 147, member 146, point 185, lines 151, 152 and 118 to the source of power. At the same time, current flows from lines 106 through line 153, point 154, member 158, lines 157, 181, through motor 62, thence back through lines 132, 156, member 155, point 186, lines 151, 152 and 118 to the source of power.

When controller 104 is shifted to the right, current flows from the source of power

through lines 106, 107, 160, 161, point 162, member 166, lines 165, 123, through motor 32, thence back through lines 122, 164, member 163, point 187, lines 151, 152 and 118 to the 5 source of power. At the same time, current from line 160 divides, and flows through line 169, point 170, member 174, lines 173, 139 through motor 52 and back through lines 140 and 172, member 171, point 188, lines 151, 152, 10 and 118 to the source of power.

Briefly summarizing the control arrangement, the shifting of any control member to the left operates to effect simultaneous paying in of the two cables controlled thereby, 15 while the shifting of any controller to the right pays out the two cables controlled thereby. When one group of cables is wound in, the opposite group may be selectively paid out, if desired. Furthermore, any one motor 20 may be grouped with different motors depending upon the pair of cables, which are to be wound in or paid out respectively.

To raise the chute, controllers 101 and 102 25 can both be shifted to the left. This causes all cables to be wound in simultaneously. Conversely, when such controllers are shifted to the right, all cables are paid out simultaneously. The same result can also be accomplished by shifting controllers 103 and 104 30 simultaneously, either to the left, or to the right.

An important advantage of my invention 35 is the fact that each cable is controlled by an independent motor, thus obviating the necessity for the use of clutches, control levers, connecting links and the like between the cable drums and the control house. Furthermore, the operator's attention is not required 40 for the expenditure of muscular energy in the manipulation of such control members, wherefore, his undivided attention may be directed toward the delivery end of the chute. By grouping the motors to effect simultaneous 45 operation of them in pairs, and by employing reversible motors, I reduce to a minimum, the number of motors required to effect the desired chute manipulation, without requiring the use of mechanical disengagable connections.

50 I claim:

1. A car dumper, having a discharge chute, 55 four cables operatively connected to the chute for manipulating it, an electric motor operatively connected to each cable, and single means for operating said motors in groups.

2. In a car dumper, the combination with a support, of a discharge chute mounted for universal movement adjacent the end of the 60 support, a plurality of cables operatively connected to the chute adjacent the lower end thereof, electric motors operatively connected to said cables, there being one motor for each cable, said motors being mounted upon 65 the support, and single means remote from

the motors for controlling two of them simultaneously.

3. In a car dumper, the combination with a discharge chute, of means for supporting it for universal movement, said means including flexible members operatively connected to the chute at spaced points, an electric motor for each member, and single means for simultaneously operating some of said motors in one direction.

4. In a car dumper, the combination with a material discharge chute, of means supporting it for swinging movement, said means including flexible members operatively connected to the chute adjacent the lower end 70 thereof, an electric motor operatively connected to each of said members, said motors being reversible, whereby one member may be wound in while the other is being paid out, and single means for operating two of said 75 motors either in a forward or reverse direction.

5. In a car dumper, the combination with a material discharge chute, of cables operatively connected thereto, for moving one end 80 of the chute universally with reference to the other end thereof, an electric motor for operating each cable, and single means for grouping the operation of the motors, whereby some 85 of the cables may be wound in while the others are being paid out.

6. In a car dumper, the combination with a material discharge chute, of means for supporting it for universal movement, said means including four cables operatively connected to the chute adjacent the four corners of a rectangle, an electric motor operatively connected to each of said cables, and single means for grouping the operation of the motors, 90 whereby two of the cables may be wound in 100 while the remaining two are paid out.

7. In a car dumper, the combination with a material discharge chute supported for universal movement, four cables operatively connected to the chute, an electric motor for each 105 of said cables, and single means for grouping the operation of said motors, whereby two of the cables may be wound in independently 110 of the remaining cables.

8. In a car dumper, the combination with a support, of a discharge chute mounted for universal movement, a plurality of cables operatively connected to the lower end of the chute, an electric motor for actuating each 115 cable, and single means for grouping the operation of said motors whereby some of the cables may be wound in or paid out independently of the other cables.

9. In a car dumper, the combination with a discharge chute, of four cables operatively connected to the chute adjacent the bottom thereof, and adjacent the four corners of a rectangle, an electric motor operatively connected to each cable, and single means for 120 125 130

selectively operating any one motor with either one of two of the other motors.

10. In a car dumper, the combination with a support, of a material discharge chute mounted for universal movement with reference to the support, four cables extending from the support and operatively connected to the chute, an electric motor for actuating each cable, and single means for selectively operating any one of said motors simultaneously with either one of two of the other of said motors, whereby two of the cables may be simultaneously wound in or paid out, and whereby any one cable may be simultaneously wound in or paid out with either one of two other cables.

11. In a car dumper, the combination with a material discharge chute and means for supporting it for universal movement, four cables operatively connected to the chute, an electric motor for operating each cable, and single means for simultaneously operating one pair of motors to wind in two of the cables, and simultaneously operating the other two motors for simultaneously paying out the other two cables.

12. In a car dumper, the combination with a material discharge chute, of means for supporting it for universal movement, four cables operatively connected to the chute, for controlling the movement thereof, an electric motor for each cable, and single means for selectively grouping the operation of the motors so that anyone may be operated either in a forward or reverse direction simultaneously with either one of two of the other motors either to wind in or pay out the associated cables.

13. In a car dumper, the combination with a discharge chute, means supporting it for universal movement, four cables operatively connected to the chute for controlling the movement thereof, an electric motor for each of said cables, and single means for simultaneously operating all of said motors in the same direction either to wind in or pay out all of said cables simultaneously, said means being operable selectively to permit winding in of two of the cables, while the remaining two are being paid out.

14. In a car dumper, the combination with a support, of a material discharge chute mounted for universal movement thereon, four cables operatively connected to the chute adjacent the bottom thereof, and adjacent the four corners of a rectangle, a reversible electric motor operatively connected to each cable, and single means for selectively grouping the operation of the motors so that any cable may be wound in or paid out simultaneously with either one of the two cables spaced at the adjacent corners of the rectangle.

In testimony whereof, I hereunto affix my signature.

65 ROBERT W. KALTENBACH.
